ICE CREAM FREEZER

Ford Se Bastian, Chicago, Ill., assignor to Chicago
Electric Manufacturing Company, Chicago, Ill.,
a corporation of Illinois

Application December 10, 1949, Serial No. 6,555

Term of patent 14 years

(Cl. D67—2)

To all whom it may concern:

Be it known that I, Ford Se Bastian, a citizen of the United States, residing in Chicago, Cook County, State of Illinois, have invented a new, original, and ornamental Design for an Ice Cream Freezer, of which the following is a specification, reference being had to the accompanying drawing, forming a part thereof:

Fig. 1 is a front elevational view of an ice cream freezer, showing my new design;

Fig. 2 is a fragmentary side elevational view thereof with the bottom portions omitted for convenience of illustration;

Fig. 3 is a top plan view thereof.

The dominant features of my design reside in the portions illustrated in solid lines.

I claim:

The ornamental design for an ice cream freezer, as shown and described.

FORD SE BASTIAN.
